UNITED STATES PATENT OFFICE

144,136

DESIGN FOR A CAMERA

Verneur E. Pratt and George F. Gray,
Norwalk, Conn.

Application October 9, 1945, Serial No. 122,686

Term of patent 14 years

(Cl. D61—1)

To all whom it may concern:

Be it known that we, Verneur E. Pratt and George F. Gray, citizens of the United States and residents of Norwalk, county of Fairfield, and State of Connecticut, have invented a new, original, and ornamental Design for Cameras, of which the following is a specification, reference being had to the accompanying drawings, forming part thereof, in which:

Figure 1 is a front elevational view of a camera showing our new design, the same being drawn on a smaller scale than the disclosures in Figures 2 and 3.

Figure 2 is a side elevation showing one of the front panels open and forming a feed table; and

Figure 3 is a perspective view showing the feed table in operative position and also showing the control panel adjacent thereto.

The back and side of the camera not shown are plain.

We claim:

The ornamental design for a camera as shown and described.

VERNEUR E. PRATT.
GEORGE F. GRAY.
